SKIRT AND METHOD OF MAKING SKIRTS

Arthur M. Kay, Taos, N. Mex.

Application February 15, 1952, Serial No. 271,817

3 Claims. (Cl. 2-211)

1

This invention relates to skirts, and more particularly to a pieced skirt comprising a plurality of connected fabric segments.

One important object of the present invention is to provide a skirt falling within the general category referred to that can be readily fashioned from a plurality of either identical or unidentical simply designed segments, thus to permit all of said segments to be cut simultaneously from superposed pieces of fabric.

Another important object is to provide a skirt as stated so designed as to permit the several segments to be stitched to one another speedily and easily.

Yet another important object is to provide a skirt of the type stated so designed as to permit a full skirt of the pleated, folded, gathered or plain type to be formed swiftly from a number of like or unlike, simply cut fabric members.

Other objects will appear from the following description, the claims appended thereto, and from the annexed drawing, in which like reference characters designate like parts throughout the several views, and wherein:

Figure 1 is a perspective view of a skirt formed in accordance with the present invention, as it appears when being worn;

Figure 2 is a top plan view of a completed skirt;

Figure 3 is a plan view of the several segments as they appear in blank prior to being stitched together to form the end product;

Figure 4 is a fragmentary perspective view of the upper portion of the skirt, showing slide fastener means for securing the skirt about the waist of a wearer;

Figure 5 is an enlarged, detail, sectional view taken on line 5-5 of Figure 2 illustrating the means whereby the contiguous segments are secured to one another;

Figure 6 is an enlarged sectional view taken on line 6-6 of Figure 2, showing the arrangement whereby I attach the skirt portion to the waistband;

Figure 7 is similar to Figure 3, showing a modified form;

Figure 8 is a view similar to Figure 1, showing another modification;

Figure 9 is a side view of a completed skirt formed from the segments illustrated in Figure 8;

Figure 10 is a plan of a blank from which the segments of another modified form of skirt are cut;

Figure 11 is a view similar to Figure 9, showing a skirt made from the segments of Figure 10;

Figure 12 is a view similar to Figure 10, showing another modification; and

2

Figure 13 is a view similar to Figure 9, showing a skirt made from the segments of Figure 12.

Referring to the drawings in detail, the reference numeral 10 has general application to a waistband connected to the upper end of a skirt portion, generally designated 12, said waistband and skirt portion cooperating to form the completed skirt.

Referring to Figure 3, a rectangular piece of material from which the several segments that make up the completed skirt is cut appears in dotted lines, and has been designated 14. In the form of the invention illustrated in Figures 1 to 6, inclusive, four fabric segments and a waistband are cut from said piece of material. It should be noted at this point, however, that more or less segments can be used, if desired, four being illustrated in Figure 3 merely to show one presently preferred embodiment of the invention.

Considering first the formation of the waistband 10, this is fashioned from an elongated, rectangular piece of material folded longitudinally and centrally upon itself, as at 16.

The waistband, it should be noted, can be of any desired type, that is, it can be folded, pleated, gathered, elasticized, or plain.

The several fabric members cooperating to form the completed skirt have been designated 18, and are of identical dimensions and shape, thus to permit their being cut simultaneously from superposed pieces of material, if desired. Thus, the skirt which I have designed lends itself readily to mass production methods.

Since all the fabric members 18 are of identical formation, one only will be described. This is formed as a segment or sector of a ring having an arcuate bottom edge 20 extending through 180° of a circle, and an arcuate top edge 22 concentric with the bottom edge and also extending through 180° of a circle. The opposite side edges of the sector are designated 24, and are of straight formation, said side edges being aligned longitudinally with one another when the sector is in blank, and extending between the respective ends of the top and bottom edges 22, 20, respectively. The side edges 24 are preferably formed with seams or hems 26.

In forming the completed skirt, the several sectors 18 are pleated, folded or gathered radially, as at 28, and have their respective side edges 24 connected to the adjacent side edges of contiguous sectors by lines of stitching 30. Thereafter, the waistband 10 is folded upon itself along the line 16, so as to be given an inverted, U-shaped, cross-sectional configuration (Figure 6). The waistband is then positioned over the top

edges of the connected segments so as to straddle the same, and is secured to the connected segments by lines of stitching 32.

One of the lines of stitching 30 terminates short of the waistband 10, so as to permit slide fastener elements 34 to be applied to the contiguous side edges of a pair of the segments, in a manner well known to those skilled in the art. Then, to secure the waistband about the waist of the wearer, gripper fastener elements 36 are applied to the opposite ends of the waistband. It will be understood that other forms of fastener elements can be utilized, if desired.

With respect to the openings of the skirt, the use of an elastic or gathered waistband can eliminate an opening, and, therefore, the openings should be covered, to be closed either with slide fasteners, buttons, snaps, hooks and eyes, or gussets. A bellows gusset, if used, could be closed with any of the several types of fasteners listed.

It is to be noted that the four sectors illustrated in Figure 3, when in blank, extend through a distance sufficient to form two circles. However, the pleating, folding or gathering of the segments halves the distance between the side edges of each sector, and also halves the length of the top and bottom edges 22, 20 of each sector. As a result, when the several sectors are stitched to one another, they will extend through 360° of a circle, as may be readily noted by reference to Figure 2.

In the form of the invention illustrated in Figure 7, there is illustrated an arrangement wherein in eight segments or sectors are used rather than four. In this instance, each sector 38 extends through 90°, having an arcuate bottom edge 40 concentric with an arcuate top edge 42. As in the first form of the invention, each sector 38 has radial, straight side edges 44.

In forming the skirt illustrated in blank in Figure 7, the identical sectors 38 are pleated, folded, or gathered in the manner referred to hereinabove to halve their size, after which the side edges thereof are stitched to one another and a waistband 10 applied as in the first form of the invention.

In some instances, it may be desired to form a slit skirt, in which event a part or all of one or more of the lines of stitching 30 may be omitted.

Further, the outer or bottom portion of the skirt illustrated in Figure 2 might be a piece of material separate from the inner or top portion of the skirt. These changes are believed to be sufficiently obvious as not to require special illustration, and are mentioned merely to show other arrangements not departing from the spirit of the invention as claimed.

It may be noted that although the connecting of the several sectors illustrated in Figures 3 and 7 will cause the outer edges thereof to extend through 360° of a circle, this fact per se is not the critical feature of the invention, and has been brought out hereinbefore merely to show how the completed skirt will appear when the sectors are connected to one another. It is a characteristic of conventionally formed skirts, in fact, that the bottom edge would define a circle of 360° if the conventional skirt was placed upon a form and viewed from below. The essence of the invention, it should be emphasized, lies in the use of particularly formed sectors which, when connected to one another, will form a full, pieced skirt.

In Figure 8 there is illustrated a modified form

of the invention, wherein I provide four sectors 46, each of which extends through 90°, each sector having radial, straight side edges 48 disposed at right angles to one another and cut along the straight of the material or fabric, an arcuate bottom edge 50, and an arcuate top edge 52 concentric with said bottom edge.

This particular pattern also includes four relatively narrow segments 54 of less than ninety degrees and having arcuate bottom edges 56 concentric with arcuate top edges 58. The side edges 60 of the sectors 54 are also straight and radially arranged, but are disposed at acute angles to one another and cut on a bias.

The sectors 46, 54 can be connected together to form a skirt, as illustrated in Figure 9, said sectors being stitched along their top edges to a waistband 10, such as has been herebefore illustrated and described. Said waistband can, of course, be of any desired type.

The completed skirt illustrated in Figure 9 has been generally designated 62, and has a full sweep such as that obtained in using the pattern illustrated in Figure 7. However, the completed skirt will differ from that illustrated in Figure 2, for example, in that the radial gathers 64 thereof will extend upwardly from the bottom edge of the skirt, but may terminate short of the waistband, so as to leave a plain portion 66 extending about the upper portion of the skirt below the waistband, if so desired.

Also, it will be apparent from Figures 8 and 9 that the segments 46 will be alternated with the narrower segments 54 in producing the completed garment so that the longitudinal edges of the larger segments 46 which are cut on the straight of the material or fabric will be joined to the adjoining longitudinal edge of the adjacent narrower segment 54 in which the longitudinal edge has been cut on the bias.

In this connection, the particular cuts illustrated in Figure 8 can be changed, with the larger sectors 46 being divided into several pieces, if desired. The narrow sectors 54, additionally, can be individually divided or even enlarged.

In Figure 10 I have illustrated a blank from which a plurality of elongated, rectangular sectors 68, 70, 72 can be cut, together with a waistband 10. These sectors are cut along their respective longitudinal edges, and are used in forming a skirt illustrated in Figure 11.

The skirt of Figure 11 is made in three tiers or flounces, but it will be readily appreciated that it can be made in a fewer number of tiers, or more tiers, if desired. Each of the rectangular segments is gathered throughout its length, and is secured to the contiguous, longitudinal edge of the tier next above, so as to form the completed skirt. Thus, the completed skirt is of the tiered type, the segments 68 having gathers 84, the segment 70 having gathers 86, and the segment 72 having gathers 88 extending fully to the waistband 10.

In Figure 12 there is illustrated a blank or pattern from which segments 74, 76 and 78 are cut to be used in the manufacture of a skirt illustrated in Figure 13. The segment 74 and the segment 76 are of elongated, rectangular configuration, the segment 74 being appreciably longer than the segment 76. A waistband 10 can be cut from the same piece of material, if desired.

The uppermost segment 78, as will be readily noted from Figure 12, has an arcuate bottom edge 80 extending through 180° of a circle, and

an arcuate top edge 82 also extending through 180°, and arranged concentrically to the bottom edge.

The use of an arcuate segment 78 permits a tiered skirt to be manufactured, wherein the lowermost tier 74 has gathers 90, and the middle tier 76 has gathers 92. The uppermost tier, however, is plain.

It is understood, of course, that the waistband can be gathered, plain or of some other desired type in any of the forms illustrated in the several figures of the drawings.

It will be apparent from the foregoing that there is also illustrated and described a method of making a pieced skirt which includes cutting from an elongated rectangular blank of material along each of the opposite sides of a longitudinal center line a pair of spaced major sectors 46, in the case of the form of the invention shown in Figures 8 and 9, of 90 degrees each and cutting a pair of minor sectors 54 of less than 90 degrees each with the upper and lower arcuate edges of each of the sectors cut concentrically from the area between the spaced major sectors, spacing the inner radial edges 48 of the major sectors 46 from the longitudinal center line of said blank, cutting from the longitudinal central area of material between the said inner radial edges an elongated rectangular piece defining a waistband and an additional pair of minor sectors, similar to the sectors 54, of a circle of less than 90 degrees with upper and lower arcuate edges cut concentrically, alternatingly sewing the radial edges of the major sectors together with the radial edges 60 of the minor sectors, gathering each of the sectors and folding said waistband along its longitudinal center line and securing it in its folded position over the inner arcuate edges of said sectors.

With regard to the forms of the invention as shown in Figures 1 through 6, as well as a form of the invention in Figures 7 and 8, there is illustrated and described a method of making a pieced skirt which includes cutting from an elongated rectangular blank of material along opposite sides of the longitudinal center line sectors of a circle totaling 180 degrees in each side of the material with the upper and lower arcuate edges cut concentrically in each sector, spacing the inner adjacent radial edges of each sector from and adjacent the longitudinal center line of said blank, cutting from the area of material between the inner radial edges an elongated rectangular piece which defines a waistband, and cutting from the blank additional sectors having the same radii as the first mentioned sectors with their upper and lower arcuate edges of the same angular extent and in concentric relation, sewing the adjoining radial edges of said sectors together, gathering each of the sectors, and then securing the inner arcuate edges to the waistband to form a skirt. Or, as hereinbefore specifically pointed out, the waistband will be folded longitudinally at its center line and secured to the adjoined inner arcuate edges of the sectors so as to extend upon either side thereof so that the waistband is folded over to conceal the gather, with the gathers formed in the upper arcuate edges of the sectors and thereby making the garment more comfortable upon the body of the

is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims. Thus, the skirt might be formed as a part of a complete dress. Then, again, in some instances, the waistband might be eliminated, and in still another instance, the skirt might be formed from smaller segments than those illustrated.

15 What is claimed is:

1. A pieced skirt comprising four fabric members formed as a sector of a ring and having concentric top and bottom edges extending through ninety degrees of a circle and with the longitudinal edges thereof cut on the straight of the fabric, four additional fabric members

20 formed as sectors of a ring having concentric top and bottom edges extending through less than ninety degrees of a circle and with the longitudinal edges thereof cut on a bias, said fabric members and said additional fabric members being secured together in alternating relation to have a straight cut longitudinal edge adjoining a bias cut longitudinal edge, each of said members and said additional members having pleats which reduce the distance through which said top and bottom edges extend so that when joined they will extend through three-hundred and sixty degrees of a circle in a flat surface, and a waist 25 band folded along its longitudinal center line secured over said top edges of said members and said additional members.

2. A method of making a pieced skirt which including cutting from an elongated rectangular blank of material along opposite sides of the longitudinal center line sectors of a circle totalling one-hundred and eighty degrees in each side of the material with the upper and lower arcuate edges cut concentrically in each sector, spacing the inner adjacent radial edges of each sector from and adjacent the longitudinal center line of said blank, cutting from the area of material between said inner radial edges an elongated rectangular piece to define a waist band, cutting from said blank additional sectors having the same radii as first mentioned sectors with their upper and lower arcuate edges of the same angular extent and in concentric relation, sewing the adjoining radial edges of said sectors together, gathering each of said sectors, and securing the inner arcuate edges to said waist band to form a skirt.

3. A method of making a pieced skirt which includes cutting from a rectangular blank along each of the opposite sides of a longitudinal center line a pair of spaced major sectors of a circle of 90 degrees each and cutting a pair of minor sectors of less than 90 degrees each with the upper and lower arcuate edges of each of the sectors cut concentrically from the area between the spaced major sectors, spacing the inner radial edges of the major sectors from the longitudinal center line of said blank, cutting from the longitudinal central area of the material between said inner radial edges an elongated rectangular piece defining a waistband and an additional pair of minor sectors of a circle of less than 90 degrees with upper and lower arcuate edges cut concentrically, alternatingly sewing the radial edges of the major sectors together with the radial

It is believed clear that the invention is not necessarily confined to the specific use or uses thereof described above, since it may be utilized for any purpose to which it may be suited. Nor

7
edges of the minor sectors, gathering each of said sectors and folding said waistband along its longitudinal center line and securing it in its folded position over the inner arcuate edges of said sectors.
